DESIGN FOR A VEGETABLE GRATER

Rose Mary Muller, Port Washington, N. Y.

Application February 24, 1943, Serial No. 109,616

Term of patent 14 years

To all whom it may concern:

Be it known that I, Rose M. Muller, a citizen of the United States of America, residing at Port Washington, in the county of Nassau and State of New York, have invented a new, original, and ornamental Design for a Vegetable Grater, of which the following is a specification, reference being had to the accompanying drawing, forming a part thereof.

I claim:

The ornamental design for a vegetable grater, as shown.

ROSE MARY MULLER.
